UNITED STATES PATENT OFFICE.

ERNEST DAVIS, OF DELPHOS, KANSAS.

SAFETY-STIRRUP.

1,231,571.

Specification of Letters Patent.

Patented July 3, 1917.

Application filed October 9, 1916. Serial No. 124,610.

To all whom it may concern:

Be it known that I, ERNEST DAVIS, a citizen of the United States, residing at Delphos, in the county of Ottawa, State of Kansas, have 5 invented certain new and useful Improvements in Safety-Stirrups; and I do hereby declare the following to be a full, clear, and exact description of the invention, such as will enable others skilled in the art to which 10 it appertains to make and use the same.

This invention relates to improvements in stirrups, and particularly to safety stirrups.

One object of the present invention is to provide a device of this character which is 15 simple in construction, and effective in its operation.

Another object is to provide a device of this character wherein the hinge connections of the operative parts are effectively concealed and protected from contact with the 20 clothing of the rider.

Other objects and advantages will be apparent from the following description when taken in connection with the accompanying 25 drawing.

In the drawing:

Figure 1 is an elevation of a stirrup made in accordance with my invention.

Fig. 2 is a side elevation thereof.

30 Fig. 3 is a transverse sectional view taken on the line 3—3 of Fig. 1.

Fig. 4 is a transverse sectional view taken on the line 4—4 of Fig. 3.

Referring particularly to the accompanying drawing 10 represents the body of the stirrup, to the upper end of which is connected the stirrup strap. The tread plate 11 is hinged to one side of the lower end of the stirrup, as shown at 12, while the other end 35 is reduced, as at 13 and engages within the bifurcation 14 at the lower end of the other side of the stirrup. Through the bifurcation there are formed the alining openings 15, which are adapted to register with an opening 16 formed in the reduced end 13 of the tread plate.

40 Engaged in the forward side of the stirrup body are two forwardly extending lugs 17, in the outer end of each of which is formed a transverse opening 18. An ar-

cuate trip member 19 is disposed in front of 50 the stirrup, and is arcuate in cross section, as clearly shown. Within the cross-sectional arcs of the legs of the trip member are disposed the apertured ends of the said lugs, and bolts or screws 20 are passed through 55 the trip member and the apertured lugs, thus providing a pivotal support for the trip member and effectively concealing the mounting from view and from danger of catching in the rider's clothes. The lower 60 end of one leg of the trip member has pivotally connected thereto a latch bolt 21 which normally is disposed through the openings in the before-mentioned bifurcation and in the aperture of the reduced end of the tread 65 plate. On each of the screws 20 is engaged the intermediate coil portion of a V-shaped spring 22, one arm of which is disposed within the rear face of the leg of the trip member, while the other arm has its end bent 70 at right angles and disposed in an opening 23 in the body of the stirrup. These springs bear against the trip member above its pivotal connection with the stirrup whereby the latch bolt is resiliently held with the tread 75 plate in elevated position.

Should the rider's foot slip through the stirrup, or he be thrown from the horse with his foot caught in the stirrup, the toe of his shoe would press against the trip member 80 and move the upper portion rearwardly, thereby withdrawing the latch bolt from engagement with the tread plate, and permitting the said plate to swing downwardly, and release the foot. The tread plate is firmly 85 held in elevated position to support the weight of the rider, without danger of being released.

What is claimed is:

A safety stirrup comprising a body, a 90 tread plate hinged to one side of the lower end of the body, the other end of the said plate being reduced and apertured and disposed within a bifurcation in the lower end of the other side of the body, 95 an arcuate trip member disposed forwardly of the body and being arcuate in cross section, apertured lugs carried by the

body and disposed with the cross sectional arcs of the trip member, pivot pins disposed through the trip member and the lugs, V-shaped springs having intermediate coil portions receiving the said pins therethrough, the arms of the springs bearing respectively against the trip member and the body, and a latch bolt pivotally carried by the trip

member and disposed through the bifurcation and the reduced end of the tread plate. 10

In testimony whereof, I affix my signature, in the presence of two witnesses.

ERNEST DAVIS.
